UNITED STATES PATENT OFFICE.

JOHN J. BERNET, OF CLEVELAND, OHIO.

LOCOMOTIVE TERMINAL AND METHOD OF SALVAGING FIRE.

Application filed March 11, 1925. Serial No. 14,625.

To all whom it may concern:

Be it known that I, JOHN J. BERNET, a citizen of the United States, residing at Cleveland, in the county of Cuyahoga and

5 State of Ohio, have invented certain new and useful Improvements in Locomotive Terminals and Methods of Salvaging Fire, of which the following is a specification.

This invention relates to terminals in which locomotives are cleaned or repaired, and in the use of which the fire is removed from a locomotive in order to render it accessible for the work to be done. According to practice prior to the present invention, the fire of a locomotive is disposed of by dumping it bodily into an ash pit or other receptacle, from which it is subsequently removed and disposed of as refuse, with or without the expense of a special 20 procedure for salvaging unconsumed fuel.

But even with such attempts at recovery and the exercise of care in permitting the fire to become as low as practicable before the locomotive enters the terminal, this practice involves great waste of useful fuel as well as 25 heat already generated.

The object of the present invention is to establish a method of procedure, as well as facilities for practicing the same, whereby 30 the ignited but unspent fuel discarded from the locomotive, in its glowing state and preferably without the ash, is transferred to a situation where its existing heat can be economically utilized and its combustion for 35 the generation of more heat can proceed without interruption, as, for instance, by transferring the discarded glowing fuel of the locomotive to the fire box of another steam generator, preferably a stationary 40 boiler; and, accordingly, one feature of the present invention consists in so disposing of the live portion of the fire bed of a locomotive which is dumped as a preliminary to 45 submitting the locomotive for treatment or repairs; the preferred procedure involving also the separate deposit of the ash or consumed fuel in order that substantially clean fuel alone will be transferred.

Another object of the invention is to provide a suitable plant or apparatus for use 50 in realizing the process above outlined; and, to this end, another feature of the invention consists in providing in connection with terminal trackage for locomotives, fire dumping facilities, means for catching material dumped from a locomotive fire box and

transferring such material from the place of dumping, and a steam boiler or other industrial furnace within reach of such conveying means and suitably equipped for introducing live fire into its fire box; the trackage being also preferably provided with separate means for receiving ash or spent fuel that may be discharged from the locomotive fire box; and the fire receiving and conveying means being of such nature that it will receive the unconsumed fuel in its glowing state without contamination by the ashes; also said conveying means consisting preferably of elements which receive the fire by gravity and convey it to a position within reach of a pick-up and conveying means, for instance, an overhead crane, and the means for feeding the fuel to the furnace fire being constructed to receive the fuel from the crane.

In order that the invention may be fully understood, the preferred embodiment thereof will now be described in detail in connection with the accompanying drawings, in which—

Figure 1 is a plan view, and Figure 2 a vertical transverse section on the line 2—2 of Figure 1, of that portion of a locomotive terminal involved with the invention.

A represents the fire cleaning house of a locomotive terminal in which are extended locomotive tracks B, and in which are located ash pits C in position to receive, by gravity, ashes discharged from locomotives properly spotted upon the several tracks. Each ash pit C may be constructed to serve a plurality of the tracks B and will preferably include in its construction a well D into which a pick-up bucket or other suitable instrumentality may be introduced for removing accumulation in the pit. These ash pits will also, preferably, be equipped with means, such as suggested at E in Figure 2, for delivering water over such portions of the pit as are inclined at a low angle, in order to provide a vehicle for conveying the deposited ashes to the wells D, and also for laying the dust and quenching the heat of the ash in the wells. Also located beneath the tracks B, but in positions removed from the ash pits C, are fire dumping chutes F over which locomotives may be spotted after having discharged their ashes, and each of which chutes is constructed to direct fire, by gravity, into a buggy G traveling upon a track H to a pick-up opening J where the

contents of the buggy, preferably with the body of the buggy, can be lifted by means of suitable lifting apparatus, preferably in the nature of a bridge crane K adapted to dump the contents of the buggy selectively into any one of a series of hoppers L in feeding relation to the fire grate M of a stationary boiler furnace O. By this means, unspent fuel in the glowing state, and therefore 10 without uneconomical loss of heat units already developed, can be transferred bodily to a furnace where combustion of the valuable fuel can be continued under most economical conditions, as, for instance, for the 15 generation of steam required for use around the locomotive terminal.

The furnace O will preferably have associated with it, and within reach of the crane K, a coal bunker P adapted to be supplied 20 with fresh fuel from cars running upon a track R, so that when the live fire or unspent locomotive fuel available for feeding the furnace O is insufficient for the demands 25 on the furnace, fresh fuel may be picked up by the crane K, for instance, through the medium of the grab bucket S and delivered to the furnace, preferably, however, through the stoking hopper T which will deliver in a relation to the fire which will be somewhat 30 different from that in which the glowing fuel is delivered, and which will be more appropriate for fresh or uncoked fuel. However, this is a detail which may be largely 35 a matter of choice and, like other details described in presentation of the preferred layout of the plant, may be varied as circumstances may dictate.

The buggy track H may, if desired, be continued past the pick-up hole J, and to a 40 point V located beneath the grate M of the stationary boiler, and thus made the means of removing ash from the latter, for instance, by loading a buggy G beneath the grate M, then moving it beneath the pick-up 45 opening J, and there elevating the buggy through means of the crane and dumping it into an ash car standing on the track R.

By following the method of procedure 50 herein described, and particularly when carried on through means of the apparatus disclosed or the equivalent thereof, great saving in valuable fuel may be effected. In ordinary practice, the quantity of unspent fuel discharged from locomotives preliminary to rendering them available for repair 55 or cleaning, will average one-half a ton per locomotive, and with a terminal of average capacity, may aggregate as much as ten or twelve tons per day; moreover, the quantity 60 of heat units wasted by dumping a live fire and the expense of water consumed in

quenching a dumped fire is considerable. As compared with this practice, the present invention takes the live fire with its already generated heat, and promptly transfers it to the collateral furnace, thereby effecting very great economy over prior practice, even when the latter involves treating the dumped refuse, after cooling, to salvage unspent fuel. 65

I claim:

1. In a locomotive terminal, means for receiving ashes from a locomotive fire box, means for separately receiving the fuel constituting the fire bed of the locomotive, and means for transferring said fuel while in a 70 state of ignition.

2. In a locomotive terminal, means for receiving ashes from a locomotive fire box, means for separately receiving the fuel constituting the fire bed of the locomotive, a 75 separate furnace adapted to receive fuel in a state of ignition, and means for transferring said fuel while in a state of ignition to said separate furnace.

3. In a locomotive terminal, means for receiving ashes from a locomotive, an independent means, spaced from the ash receiving means, adapted to receive in a state of ignition the fuel constituting the fire bed of the locomotive, the fuel receiving means being portable to convey the fuel away, means for elevating and dumping the fuel while in a state of ignition, and a separate furnace adapted to receive the burning fuel from the elevating and dumping means. 85

4. The improvement in the art of cleaning locomotives, which consists in salvaging the burning fuel from the fuel bed of a locomotive by discharging the fire box of the locomotive and transferring it while 100 still in a state of ignition to another furnace.

5. The improvement in the art of cleaning locomotives, which consists in salvaging the burning fuel from the fuel bed of a locomotive by first separating ash from the fuel 105 bed and then separately discharging the fire box of the locomotive and transferring it while still in a state of ignition to another furnace.

6. The improvement in the art of cleaning locomotives, which consists in salvaging burning fuel from the fuel bed of a locomotive by first spotting the locomotive over an ash receiver and there discharging ashes from the fuel bed, then spotting the locomotive over a fuel receiver, discharging the burning fuel thereto and, while the fuel is in a state of ignition, transferring it to another furnace. 115

Signed at Chicago, Ill., this 2 day of 120 February, 1925.

JOHN J. BERNET.
